Fraser, Myers Manley.

UNITED STATES PATENT OFFICE

JOHN WAHL, OF ROSEDALE, NEW YORK, ASSIGNOR TO A. SCHRADER'S SON, INCORPORATED, OF NEW YORK, N. Y., A CORPORATION OF NEW YORK

DEFLATING MACHINE

Application filed March 5, 1930. Serial No. 433,371.

The present invention relates to tube deflating machines and aims to provide certain improvements therein.

In prior constructions of deflating machines of the general type to which the present invention is directed, it has been the usual practice to employ mechanical means in cooperative relation with the foot of a valve stem to maintain the walls of the tube separated at the point whereat the air is exhausted until substantially all the air has been evacuated from the tube, and to also employ expandible means for engaging the inner periphery of the tube to cause its collapse during the evacuating operation. In still other constructions it has been proposed to rely upon various novel arrangements of supporting the tube whereby the mechanical means at the foot of the valve were dispensed with. Most of the prior constructions have been fairly efficient. Some have been displaced because of their bulkiness, others because of their lack of ease in operation, and still others because of the fact that the deflated tube did not lie flat nor conveniently lend itself to rolling or folding for packing, without buckling. This latter objection was particularly evident in tire tubes which are formed on curved mandrels.

According to the present invention I provide a machine in which the enumerated objections are obviated and which contains novel and efficient means for supporting the tube in a manner such that the walls of the tube will remain spaced apart at the foot of the valve stem throughout the deflating operation, and one which causes the tube upon deflation to assume a shape which facilitates the rolling or folding of the tube for packaging. The invention also includes other features of novelty, all of which will be understood from the detailed description which follows, when considered in conjunction with the accompanying drawing, wherein

Figure 1 is a fractional elevation of a tube deflating machine with parts thereof shown in section.

Fig. 2 is a similar view of a slightly modified form of the invention.

Fig. 3 is a fractional top plan view of the machine shown in Fig. 1.

Fig. 4 is a longitudinal section of a preferred form of valve opener for use with the present invention.

Fig. 5 is a top plan view of a detail of the invention shown in Fig. 1.

Referring first to Figs. 1, 3 and 5 of the drawing, let A indicate a base upon which is mounted a vertical upright or standard B formed at its top with a hollow bearing C having an external circumferential groove c which communicates with the hollow interior of the bearing through openings c'. Connected to the top of the interior of the bearing C is a tube D communicating with a suction pump (not shown).

Rotatably mounted upon the bearing C is a movable carrier E having a plurality of radial ducts e communicating with the interior of the bearing C through the groove c and opening c'. The carrier E has mounted therein a plurality of supporting arms F each of which is preferably in the form of a rigid tube communicating with a duct e in the carrier. Said supporting arms F are preferably horizontally disposed and include an angularly disposed portion f, the free end of which is closed by a cap f' or the like, said portion f' forming with the horizontally disposed arm F an angle of approximately 135°.

Mounted upon each arm F intermediate its ends through the medium of a suitable hollow T-fitting G and nipple g is a casing H within which is fitted valve opener means which comprises a check valve h normally held against a packing h' by a coil spring h², one end of which presses against a shoulder on the check h and the other end of which bears against a shoulder j provided within a plug element J fitted within the casing H. The check valve at its seating end is provided with a projection h³ which extends through the packing h' and is adapted to engage the end of a valve pin of the tire valve to unseat the same when said tire valve is inserted into the open end of the casing and pressed against the packing h'. The tire valve unseating element or opener h³ is provided with a tapered end to simultaneously unseat the tire valve and check valve h and is quite analogous to

the valve unseating means used in valve chucks for many years. For guiding the nipple end of the tire valve into engagement with the valve opener, the forward or leading end of the casing H is flared outwardly, as shown at h^4 , said outwardly flared portion connecting with a reduced bore h^5 through an intermediate bore h^6 which latter is preferably lined with antifriction material.

- 10 For establishing communication between the interior of the plug J and the casing H, the former is provided with a reduced end which provides an annular groove j' and with spaced radial openings j^2 leading from 15 said annular groove to the interior of the plug J. For providing a leak-tight seal between the plug J and casing H, a packing j^3 is fitted between the rear end of said casing and an enlarged head on the plug J. For 20 guiding the check valve in its movements, it is provided with a stem h^7 which is slidable in a bore j^4 in the plug. The interior of the plug J being in communication with the suction tube D through the medium of tube 25 F. T-fitting G, nipple g, groove j' and openings j^2 , it will be apparent that the pressure exerted by the spring h^2 upon the valve h must be sufficient to overcome the suction effect upon the back of said valve.
- 30 Mounted upon each arm F and disposed in line with the axis of the valve opener h^3 is a support K for a pneumatic tube to be deflated, which support K comprises an arm k extending longitudinally and preferably in 35 superposed relation to the arm F, the end of said arm k nearest to the valve unseating means being curved upwardly to form a seat or cradle for a pneumatic tube, the upwardly extending end of said arm being bifurcated 40 or forked, as shown at k' , k' in Fig. 5. The distance between the arms or prongs of the fork is sufficient to receive therebetween the valve stem of the pneumatic tube to be deflated, and the end faces of said prongs are 45 tapered toward each other, as shown at k^2 , k^2 , at an angle corresponding to angles provided by the divergent wings of a bridge washer with its base. The height of the prongs k' is such that when the valve stem of a pneumatic tube to be deflated is received within 50 the forked end of the support K between the tube and the bridge washer, the lower edge of the bridge washer will seat on the base k^5 of said forked end, and function to support 55 said tube thereon.

The tube support K is carried by a fitting L which is slidably mounted upon the arm F, the rear end of the support being guided in its sliding movement by passing through 60 a guide opening formed in a member M which is rigidly mounted in upright position upon the arm F. Pivotally mounted to the top of the member M is an operating lever N which is connected with the top of the element L through the medium of a link 65

O, the ends of which are pivotally connected respectively to the top of the element L and to the lever N intermediate its ends. The free end of the lever N is fitted with a weighted handle n, which upon being raised, will act through the link O to cause the element L to slide along the arm F and carry with it the support K. Conversely, when the end n of the lever is moved downwardly it will move the upturned end of the support K toward the valve opener. To limit the support in its forward movement it is provided with a stop pin k^6 .

In lieu of the lever and link connection L, M, N, O for controlling the movement of the tube support, as shown in Fig. 1, I may employ the modified form of tube support K' shown in Fig. 2, wherein the rear end of the support is provided with a downwardly projecting lug k^3 having an axial opening through which extends the arm F and upon which said support is slidable. For guiding and preventing relative circumferential movement of the support upon the arm, any suitable means may be employed, for example, the sides of the arm F may be grooved, as indicated by the reference character f^2 , and the lug k^3 may be fitted with pins k^4 engaging in said grooves. The pin and groove connection k^4 , f^2 can also serve to limit the axial movement of the support K' on the arm F. Normally it is intended that the support F be urged toward the valve opener means so that when a tube is mounted on said support the valve stem thereof will be automatically moved against the valve opener to unseat the tire valve. For accomplishing this end, I mount in encircling relation upon the arm F, a spring P and provide an abutment for said spring by rigidly securing a 95 collar Q to said arm.

In the operation of the device two operators are preferably employed, the duty of the first being to mount the tire to be deflated upon the supports, and the duty of the second being merely to remove the deflated tires from the supports when they reach him, the rate at which the tubes are deflated being controlled so that a tire will be completely deflated in the rotation of the carrier E from the first operator to the second. More specifically, the deflating operation is carried out as follows:

The first operator will mount the tube on the support K or K' in a manner such that the forked arm will engage between the tube and the bridge washer on the valve stem, with said stem directed toward the valve opener. With the construction disclosed in Fig. 1, the end of the lever N is then pressed downwardly to move the end of the valve against the valve opener. The weight of the handle n is sufficient to hold the end of the valve stem against the packing h' in tire valve opening position. With the apparatus 120

disclosed in Fig. 2 substantially the same procedure is followed excepting that the spring P will normally move and hold the valve in valve opening position. With the construction of Fig. 1 in the course of time, or if desirable, to begin with, the parts may be so proportioned and weighted that the weight of the handle n will automatically, due to the action of gravity thereon, move and hold the tube support in proximity to the valve opener. In this event, when mounting a tube to be deflated it will be necessary for the operator to first move the support away from the valve opener to permit the mounting of the tube thereon, and upon releasing or lessening the applied force counteracting that of the weight of the handle, the valve will be moved to valve opening position. The tube R is then mounted upon the support with portions r and r' thereof disposed on opposite sides of the support, as best shown in dotted lines in Figs. 1, 2 and 3. When so positioned, the tube is sent on its circuit around the bearing C either by being given a gentle push by the operator or by mechanical means for rotating the carrier E at a predetermined rate. The mounting of the tubes R is continued by the first operator, and as deflation progresses the portions of the tubes on opposite sides of the support will fall and assume substantially semi-circular forms which will have a substantially flat condition, as best shown in full lines in Figs. 1 and 3, by the time said tubes reach the second operator, whereupon said tubes are removed from the support by merely moving the tube support K or K' away from the valve opener and lifting the deflated tube from said support.

I have found that because of the angular relation between the supporting arms F and f and the relative position of the valve opener with respect to said angular portions of the supporting frame, the tubes in deflated condition will assume a substantially semi-circular flat formation which admirably facilitates the rolling or folding of the tube for packaging. This is of particular value in the packaging of pneumatic tubes which have been formed on a circular mandrel, since difficulties have always been experienced in satisfactorily packaging such tubes. Of course, the invention is equally applicable to tubes formed on a straight mandrel.

While I have shown and described certain preferred embodiments of my invention and the manner in which same is to be used, I do not wish to be limited to the specific details of construction disclosed or the manner of operation defined, since these may be varied without departing from the spirit of the invention.

What I claim is:

1. In a deflating machine for pneumatic tubes or the like, a valve opener, means for bodily supporting the tube, said means being

movable with the tube to present the free end of the tube valve to the opener, and means normally urging the tube supporting means toward the opener.

2. A machine for deflating pneumatic tubes or the like, comprising a supporting arm and means for supporting a tube in a manner such that its walls will be separated at the foot of the valve, said means being movable with the tube as a unit along said arm. 70

3. A machine for deflating pneumatic tubes or the like, comprising a supporting arm, a valve opener carried by said arm, and means for supporting a tube in a manner such that its walls will be separated at the foot of the valve, said means being movable with the tube as a unit along said arm. 80

4. A machine for deflating pneumatic tubes or the like, comprising a horizontally-disposed supporting arm, a valve opener carried by said arm and disposed in parallel relation thereto, and means for supporting a tube comprising a pair of fingers which are movable with the tube as a unit along said arm. 85

5. A machine for deflating pneumatic tubes or the like, comprising a supporting arm, and a forked member slidable along said arm for engaging a tube valve stem between the walls of the tube and the wings of a bridge washer on the valve stem, the prongs of said fork being in a plane disposed transversely to the arm. 95

6. A machine for deflating pneumatic tubes or the like, comprising a supporting arm, and a tube supporting means comprising a forked member slidable along said arm and adapted to engage between the wall of a tube and the wings of the bridge washer on the tube valve stem. 100

7. A mechanism for deflating pneumatic tubes, comprising a support having portions thereof disposed substantially in a common plane at an angle to each other with the top portion of the angle of said support extending horizontally, over which support a tube to be deflated can be placed, which tube when so positioned will have portions thereof disposed on opposite sides of the plane of the support, means carried by the top portion of the support connecting with a suction device for engaging the end of the tube valve, and means for holding the tube walls spaced apart at the foot of the valve stem slidably mounted on the top portion of the support. 110

8. A deflating machine for pneumatic tubes or the like, comprising a plurality of radially-extending tube-supporting arms, each arm having means for connecting with a tube valve stem and provided with a valve opener, and with spreader means for engaging a tube to maintain its walls separated at the foot of the valve stem, said spreader 125

means being slidably mounted on the supporting arms.

9. A deflating machine for pneumatic tubes or the like, comprising a plurality of 5 radially-extending tube-supporting arms which are angular in form with one branch of each arm extending horizontally and the other branch forming an obtuse angle with the first, the horizontal branch of each arm 10 having means for connecting with a tube valve stem and provided with a valve opener, and with spreader means for engaging a tube to maintain its walls separated at the foot of the valve stem, said spreader means being 15 slidable relatively to the arm.

10. A deflating mechanism according to claim 9, wherein each of the horizontal branches of the supporting arms is provided with a passage which connects the member 20 provided with the valve opener to a suction device.

In witness whereof, I have hereunto signed my name.

JOHN WAHL.
